FIG. 13. INVENTOR:
FREDERICK JAMES PARKS
BY *George W. Swindell* ATTORNEY.

UNITED STATES PATENT OFFICE.

FREDERICK JAMES PARKS, OF CLEVELAND, OHIO.

ENVELOPE.

Application filed October 12, 1923. Serial No. 668,200.

To all whom it may concern:

Be it known that I, FREDERICK J. PARKS, a citizen of the United States, resident of Cleveland, county of Cuyahoga, and State 5 of Ohio, have invented new and useful Improvements in Envelopes, of which the following is a specification, the principle of the invention being herein explained and the best mode in which I have contemplated 10 applying that principle, so as to distinguish it from other inventions.

My invention relates to envelopes and particularly to envelopes of the self-clasp type. One form of these envelopes is patented to me by U. S. Patent No. 1,459,414; 15 one type of machines for automatically manufacturing said self-clasp envelopes is illustrated in my U. S. Patent No. 1,316,737; and an improved process for manufacturing 20 such envelopes having an automatically and detachably interlocked retaining pocket and closure flap, is patented to me by U. S. Patent No. 1,459,415.

The particular improvements of this invention reside in improved means for locking the inside ply of the pocket to the outside ply thereof, and for locking the pocket as a whole to the envelope body. Further improvements consist in providing perfect 30 closures at the corners of the envelope.

The annexed drawings and the following description set forth in detail certain means embodying my invention, such disclosed means constituting, however, but a few of 35 the forms in which the principles of my invention may be embodied.

In said annexed drawings:

Figure 1 is a plan view of the blank from 40 which one form of the improved envelopes is made;

Figure 2 is a view illustrating the state of the blank shown in Figure 1 after the completion of the initial folding thereof;

Figure 3 is a view illustrating the form 45 of said blank after the completion of the first step in the formation of the flap-receiving pocket;

Figure 4 is a view illustrating the form of 50 said blank after the completion of the flap-receiving pocket, and the interlocking of the closure flap therewith, the blank then being ready to receive the gum by means of which certain lateral tabs secure the two-ply pocket to the envelope body; whereby also 55 certain blank side flaps are secured to the

body proper to close the lateral edges of the envelope;

Figure 5 represents the blank shown in Figure 4 after applying the gum thereto;

Figure 6 represents a view of the completed envelope;

Figure 7 represents a transverse sectional view, taken in the plane indicated by the lines VII—VII, Figure 6;

Figure 8 is a view of the blank from 65 which another form of the improved envelopes is made;

Figure 9 is a view of said blank when it has been folded into the condition illustrated by Figure 4 of the first-named blank; 70

Figure 10 is a view of the completed envelope made from the blank shown in Figure 8;

Figure 11 is a plan view of the blank from 75 which a second form of the improved envelopes is made;

Figure 12 is a view of said blank when it has been folded into the condition illustrated by Figures 4 and 9 of the first two blanks, respectively; and

Figure 13 is a view of the completed envelope made from the blank shown in Figure 11.

Referring to the annexed drawings in which the several parts are indicated by the same respective ordinals in the different views, I show in Figures 1, 8 and 11, blanks from which my improved envelopes are made, the same having substantially rectangular front and back plies or portions 1 and 2 integrally joined in a transverse plane 3, the joining edge 3 forming a permanent closure along that edge of the completed envelope which shall serve as the bottom thereof. One of the plies 1 and 2, as for 90 example the ply 1, is wider than the ply 2, due to integral side flaps or extensions 4, extended along the opposite parallel side edges, these side flaps 4 being adapted to be folded over behind and sealed down upon the corresponding lateral edge portions of the rear ply 2 so as to afford permanent 95 closures along the opposite lateral edges of the completed envelope.

Along the free end of one of the plies 1 and 2, these free ends being adapted to form the mouth of the completed envelope, as, for example, the rear ply 2, is formed an integral outwardly extended two-section 105 portion, viz., sections 5 and 6, which, in the 110

completed envelope, are adapted to be folded one over the other to form a two-ply pocket, whose ends are secured beneath the adjacent ends of the side flaps 4 so as to afford this pocket along and parallel with the mouth of the envelope, open at its side opposite said mouth for the reception of a closure flap which has sections 7, 8 and 9 integrally formed along the free end of the front blank ply 1, the edge 10 of the pocket section 5, Figure 2, being adapted to register with the edge 11 of the flap section 7, when the blank is given its initial folding. This initial folding, as in fact all the subsequent foldings, is performed by machines of which one type is illustrated by my Patent No. 1,316,737 and by a process patented to me by U. S. Patent No. 1,459,415. When the blank is given its second fold so as to present the condition shown in Figure 3, the rear faces of the pocket sections 5 and 6 are brought together and at the same time the flap sections 8 and 9 are folded over, along the transverse plane 12, upon the front face of the pocket section 6 and upon the rear of the blank portion 2. When the blank is given its third fold, so as to present the condition shown in Figures 4, 9 and 12, the pocket sections 5 and 6 are transversely folded along the rear of the plane line 10 to form a two-ply pocket, the flap section 7 being conjointly folded along the plane line 11 and the flap section 8 being also conjointly folded along the plane line 13 so as to bring together the rear faces of the flap sections 8 and 9 in interlocked relation with the two-ply pocket and intermediate said pocket and the rear of the blank portion 2, the extreme terminal flap portion 9 extending from said pocket to form a pull-out tab, as plainly shown in Figures 4, 9 and 12, the rear face of the flap section 7 lying uppermost and, in conjunction with the flap section 8, completely surrounding the two-ply pocket, as also plainly shown in Figure 7. It is evident that applying paste to the lateral edges of the blank ply 2 and the ends of the pocket section 5, (Figures 4, 9 and 12), and then folding the lateral extensions 4 down upon said lateral edges of the rear blank portion 2 and the adjacent ends of the two-ply pocket will complete envelopes, such as shown in Figures 6, 10 and 13 which have been automatically formed and have a detachable interlocked pocket and closure flap for the purpose of opening the envelope for the reception of any suitable filler or for postal inspection, etc. In fact, one type of such general envelope is patented to me by said U. S. Patent No. 1,459,414. There are certain improvements, however, to such general type of envelope, in the types of envelopes shown in this application and these improvements will now be described in detail.

Referring first to the type of envelope shown in Figures 1 to 7, it will be noted in Figure 2 that certain lateral tabs 14 are formed upon the rear blank portion 2. The purpose of these tabs 14 is to secure the two-ply pocket to the body of the envelope. It will be noted that these tabs 14 are disposed somewhat forwardly of the plane line 10. Consequently, when the side flaps 4 are folded over from the position shown in Figure 4 to the position shown in Figure 6, the tabs 14 are folded down upon the outer ply of the two-ply pocket and upon the rear of the blank rear portion 2 so as securely to seal together said two-ply pocket and the body of the envelope.

Referring to the type of envelope shown in Figures 8, 9 and 10, the same includes, in combination with the improvements of Figures 1 to 7 means for insuring perfect closures at the corners of the envelope. These means comprise substantially triangular extensions 16 and 19 formed, respectively, at the extreme forward ends of the blank back portion 2 and the extreme rear ends of the closure section 7. The purpose of these extensions 16 and 19 is to insure envelope corners so tight that the envelope may safely be used for shipping seeds and other small articles. These extensions 16 and 19, in the completed envelope, assume the conditions shown in Figure 10 from which it will plainly be seen that imperforate corners for the purpose noted are formed.

After obtaining the folded condition of the envelope shown in Figure 9, it is assumed that adhesive is applied, as shown in Figure 5, before completing the envelope shown in Figure 10.

In the form of envelope shown in Figures 11, 12 and 13, in addition to the improvements described with reference to Figures 1 to 10 inclusive, I provide additional lateral tabs 15 upon the rear blank portion 2. These lateral tabs 15 are formed on the terminal edges of said blank portion 2 and are intended to provide means for securing together the two plies 5 and 6 of the two-ply pocket. It will be evident from an inspection of Figure 12 that these tabs 15 which are a part of the pocket section 6, will, when the side flaps 4 are turned over upon the rear face of the pocket section 5, be turned over and secured upon the adjacent portions of the pocket section 5 so as securely to hold together the two pocket sections. These tabs 15 are of a width materially less than the width of the adjacent sections of the tabs 14. (See Figure 12). Consequently, when the side flaps 4 are folded over, from the position shown in Figure 12 to the position shown in Figure 13, the tabs 14 are folded down over the inner ends of the tabs 15 and overlap the latter so that the tabs 14 are secured to the outer ply of

the two-ply pocket. After obtaining the folded condition of the envelope shown in Figure 12, it is assumed that adhesive is applied, as shown in Figure 5, before completing the envelope shown in Figure 13.

It will be evident from an inspection of Figures 6, 10 and 13 that the flap sections 7, 8 and 9 of each of the three types of envelopes shown and described are so tapered 10 toward the free end of the blank portion 1 that, when the side flaps 4 are sealed over to form the lateral closures for the envelope, the sealed portions of said lateral flaps 4 do not extend inwardly as far as the adjacent 15 portions of the flap portion 7. Therefore, said flap portions 7 are not sealed down by the side flaps 4 and are free to be opened, for the reception of the desired filler, for postal inspection, etc., together with the 20 other flap sections 8 and 9, by a pull upon the terminal edge of said flap section 9.

What I claim is:

1. An envelope formed from a blank, said blank consisting of a rectangular portion 25 whose free end is to be double folded, side tabs formed on said portion adjacently forward of said free end, said rectangular portion being connected to a wider second portion having side edges to be creased and 30 folded and whose free end is to be triple creased and folded, said envelope having said two portions folded upon one another, a two-ply pocket flap formed on said first-named portion on the free end thereof with the end 35 ply facing inwardly to form a pocket adjacent the mouth of the envelope, said side tabs being bent inwardly over said pocket flap and secured to the adjacent ends of said pocket flap and overlapping onto, and being secured to, the side edges of said first-named portion, side flaps formed along opposite sides of said second-named portion and folded back and secured to the side 40 edges of the said first-named portion and the corresponding edges of the said pocket flap, said side flaps covering said side tabs, and a three-ply closure flap formed on the free end of said second-named portion and folded over said pocket flap and detachably interlocked in doubled form in said pocket.
2. An envelope formed from a blank, said blank consisting of a rectangular portion 45 whose free end is to be double folded, side tabs formed on said portion adjacently forward of said free end, said rectangular portion being connected to a wider second portion having side edges to be creased and folded and whose free end is to be triple creased and folded, said envelope having said two portions folded upon one another, a two-ply pocket flap formed on said first-named portion on the free end thereof with the end 50 ply facing inwardly to form a pocket adjacent the mouth of the envelope, said two sets of side tabs being bent inwardly over the inner ply of said pocket flap, said terminal tabs underlying said first-named tabs and overlapped by the latter, said terminal tabs being secured to the inner ply of said pocket flap and said first-named tabs being secured to the adjacent ends of the inner ply of said pocket flap and overlapping onto, and being secured to, the side edges of said first-named blank portion, side flaps formed along opposite sides of said second-named blank portion and folded back and secured to the side 55
3. An envelope formed from a blank, said blank consisting of a rectangular portion 60 whose free end is to be double folded, side tabs formed on the terminal portion of said free end, said rectangular portion being connected to a wider second portion having side edges to be creased and folded and whose free end is to be triple creased and folded, said envelope having said two portions folded upon one another, a two-ply pocket flap formed on said first-named portion on the free end thereof with the end 65 ply facing inwardly to form a pocket adjacent the mouth of the envelope, said two sets of side tabs being bent inwardly over the inner ply of said pocket flap, said terminal tabs underlying said first-named tabs and overlapped by the latter, said terminal tabs being secured to the inner ply of said pocket flap and said first-named tabs being secured to the adjacent ends of the inner ply of said pocket flap and overlapping onto, and being secured to, the side edges of said first-named blank portion, side flaps formed along opposite sides of said second-named blank portion and folded back and secured to the side 70

of said pocket flap and overlapping onto, and being secured to, the side edges of said first-named portion, side flaps formed along opposite sides of said second-named portion and folded back and secured to the side 75 edges of the said first-named portion and the corresponding edges of the said pocket flap, said side flaps covering said side tabs, and a three-ply closure flap formed on the free end of said second-named portion and folded over said pocket flap and detachably interlocked in doubled form in said pocket.

3. An envelope formed from a blank, said blank consisting of a rectangular portion 80 whose free end is to be double folded, side tabs formed on the terminal portion of said free end, said rectangular portion being connected to a wider second portion having side edges to be creased and folded and whose free end is to be triple creased and folded, said envelope having said two portions folded upon one another, a two-ply pocket flap formed on said first-named portion on the free end thereof with the end 85 ply facing inwardly to form a pocket adjacent the mouth of the envelope, said side tabs being bent inwardly over the inner ply of said pocket flap and secured thereto, side flaps formed along opposite sides of said second-named portion and folded back and secured to the side 90 edges of the said first-named portion and the corresponding edges of the said pocket flap, said side flaps covering said side tabs, and a three-ply closure flap formed on the free end of said second-named portion and folded over said pocket flap and detachably interlocked in doubled form in said pocket.

4. An envelope formed from a blank, said blank consisting of a rectangular portion 95 whose free end is to be double folded, side tabs formed on said portion adjacently forward of said free end, other side tabs formed on the terminal portion of said free end, said rectangular blank portion being connected to a wider second portion having side 100 edges to be creased and folded and whose free end is to be triple creased and folded, said envelope having said two portions folded upon one another, a two-ply pocket flap formed on said first-named blank portion on the free end thereof with the end 105 ply facing inwardly to form a pocket adjacent the mouth of the envelope, said two sets of side tabs being bent inwardly over the inner ply of said pocket flap, said terminal tabs underlying said first-named tabs and overlapped by the latter, said terminal tabs being secured to the inner ply of said pocket flap and said first-named tabs being secured to the adjacent ends of the inner 110 ply of said pocket flap and overlapping onto, and being secured to, the side edges of said first-named blank portion, side flaps formed along opposite sides of said second-named blank portion and folded back and secured to the side 115

120

125

130

edges of the said first-named portion, and a three-fold closure flap formed on the free end of said second-named blank portion and folded over said pocket flap and detachably interlocked in doubled form in said pocket.

5. An envelope formed from a blank, said blank consisting of a rectangular portion whose free end is to be double folded, side tabs formed on said portion adjacently forward of said free end, other side tabs formed on the terminal portion of said free end, said rectangular blank portion being connected to a wider second portion having side edges to be creased and folded and whose 10 free end is to be triple creased and folded, said envelope having said two portions folded upon one another, a two-ply pocket flap formed on said first-named blank portion on the free end thereof with the end ply facing inwardly to form a pocket adjacent the mouth of the envelope, said two sets of side tabs being bent inwardly over the inner ply of said pocket flap, said terminal tabs underlying said first-named tabs and overlapped 20 by the latter, said terminal tabs being secured to the inner ply of said pocket flap and said first-named tabs being secured to the adjacent ends of the inner ply of said pocket flap and overlapping onto, and being 30 secured to, the side edges of first-named blank portion, side flaps formed along opposite sides of said second-named blank portion and folded back and secured to the side edges of the said first-named blank portion and the corresponding edges of the said pocket flap, said side flaps covering both sets of said side tabs, and a three-fold closure flap formed on the free end of said second-named blank portion and folded over 40 said pocket flap and detachably interlocked in doubled form in said pocket.

6. An envelope formed from a blank, said blank consisting of a rectangular portion whose free end is to be double folded, side tabs formed on said portion adjacently forward of said free end, said rectangular portion being connected to a wider second portion having side edges to be creased and folded and whose free end is to be triple 45 creased and folded, said envelope having said two portions folded upon one another, substantially triangular lateral extensions formed on said rectangular blank portion adjacent the edge by which the same is connected to said wider blank portion, a two-ply pocket flap formed on said first-named portion on the free end thereof with the end ply facing inwardly to form a pocket adjacent the mouth of the envelope, said side 50 tabs being bent inwardly over said pocket flap and secured to the adjacent ends of 55 said first-named portion, and a three-fold closure flap formed on the free end of said second-named portion and folded over said pocket flap and detachably interlocked in double form in said pocket.

7. An envelope formed from a blank, said blank consisting of a rectangular portion whose free end is to be double folded, side tabs formed on said portion adjacently forward of said free end, said rectangular portion being connected to a wider second portion having side edges to be creased and folded and whose free end is to be triple 60 creased and folded, said envelope having said two portions folded upon one another, substantially triangular lateral extensions formed on said rectangular blank portion adjacent the edge by which the same is connected to said wider blank portion, a two-ply pocket flap formed on said first-named portion on the free end thereof with the end ply facing inwardly to form a pocket adjacent the mouth of the envelope, said side tabs being bent inwardly over said pocket flap and secured to the side edges of the said first-named portion and the corresponding edges of the said pocket flap, said side flaps covering said side tabs, said triangular extensions being turned inwardly over said first-named portion and under said side flaps to form bottom leak-proof envelope corners, and a three-fold closure flap formed on the free end of said second-named portion and folded over said pocket flap and detachably interlocked in doubled form in said pocket.

8. An envelope formed from a blank, said blank consisting of a rectangular portion whose free end is to be double folded, side tabs formed on said portion adjacently forward of said free end, said rectangular portion being connected to a wider second portion having side edges to be creased and folded and whose free end is to be triple 65 creased and folded, said envelope having said two portions folded upon one another, substantially triangular lateral extensions formed on said rectangular blank portion adjacent the edge by which the same is connected to said wider blank portion, a two-ply pocket flap formed on said first-named portion on the free end thereof with the end ply facing inwardly to form a pocket adjacent the mouth of the envelope, said side tabs being bent inwardly over said pocket flap and secured to the adjacent ends of said pocket flap and overlapping onto, and being secured to, the side edges of said first-named portion, side flaps formed along opposite sides of said second-named portion and folded back and secured to the side edges of the said first-named portion and the corresponding edges of the said pocket flap, said side flaps covering said side tabs, said triangular extensions being turned inwardly over said first-named portion and under said side flaps to form bottom leak-proof envelope corners, said second-named lateral extensions being turned inwardly under the forward end of said side flaps to form top leak-proof envelope corners, and a three-fold closure flap formed on the free end of said second-named portion and folded over said pocket flap and detachably interlocked in double form in said pocket.

Signed by me this 18th day of September, 120
1923.

FREDERICK JAMES PARKS.
